UNITED STATES PATENT OFFICE.

ERICH H. LICHTENBERG, OF MILWAUKEE, WISCONSIN, ASSIGNOR, BY MESNE ASSIGNMENTS, TO KOEHRING COMPANY, OF MILWAUKEE, WISCONSIN, A CORPORATION OF WISCONSIN.

LOADER FOR CONCRETE-MIXERS.

1,387,931.

Specification of Letters Patent. Patented Aug. 16, 1921.

Application filed March 28, 1918. Serial No. 225,255.

To all whom it may concern:

Be it known that I, ERICH H. LICHTENBERG, a citizen of the United States, residing at Milwaukee, in the county of Milwaukee and State of Wisconsin, have invented certain new and useful Improvements in Loaders for Concrete-Mixers, of which the following is a specification.

The present invention has relation to the art of loading devices and comprises an improved type of loader in the form of a skip and its operating means adapted particularly for facilitating the loading of concrete aggregates into concrete mixing machines. The loading means of the invention may, however, be utilized for other purposes than in connection with concrete mixers, as will be obvious on reference to the detailed explanation of the operating means. The essential novelty of the invention resides in the provision of operating means for a loading skip including peculiar driving operating connections for raising the skip, whereby the driving mechanism or power plant employed may be utilized with the highest degree of efficiency. The driving connections allow for application of the driving forces in elevating the skip in such a manner that during the period of elevation when the load is greatest the driving forces are applied with maximum power with resultant slow speed of movement of the load, while during a later period of elevation when the resistance of the load is decreasing owing to the peculiar mounting of the skip the said driving forces operate with reduced power but increased speed in bringing the load to the point of elevation at which it is unloaded or discharged from the skip.

I am enabled to utilize the variable speed and the application of variable forces in elevating the skip and its load according to my invention by taking advantage of the method of supporting the skip, the principle of leverage obtainable by recourse to pulleys and cone shaped winding drums being employed in accomplishing the desired end.

Another feature of the present improvements involves safety provisions as a part of the hoisting mechanism whereby in the event of breakage of the hoisting cable or cables a clutch pulley or pulleys become effective to prevent accidental dropping of

the load comprising the skip alone or the skip and its contents.

These and such other objects as may hereinafter appear are attained by the novel construction, combination and arrangement of parts to be hereinafter specifically described and claimed. Reference will now be had to the accompanying drawings forming a part of this specification, wherein:

Figure 1 is a side view showing somewhat diagrammatically the supporting framework and power plant of a concrete mixer in connection with which my loading device is illustrated, full lines showing the loading skip in its load receiving position, and dotted lines showing said skip in its uppermost or discharging position;

Fig. 2 is a similar somewhat diagrammatic top plan view of the machine; and

Fig. 3 is a detail view showing more fully the formation of the snatch pulleys carried by the skip.

For an understanding of the general construction and method of operating loading skips of the type of the present invention, reference may be had to United States Letters Patent of Lichtenberg No. 1,103,788, issued July 14, 1914, and to Koehring No. 1,107,171, issued August 11th, 1914. In view of the prior art above referred to, specific references to and description of the power means for elevating the loading device or skip forming a part of this invention are unnecessary. The features of novelty in the construction at present employed differentiating the same from the said prior art will now be set forth.

A in the drawings denotes the portable concrete mixer in association with which the present invention is illustrated, said mixer comprising an upright frame B at the top portion of which is suitably mounted a shaft 1. The shaft 1 carries a relatively large drum 2 about which is adapted to wind a cable 3 which leads to a drum operable by the motor 5. Also carried by the shaft 1 are the fixed cone-shaped drums 6 disposed near opposite ends of the shaft, and about each drum is adapted to wind a cable 7 fixed to the smaller end of the drum so as to wind toward the upper end. The two cables 7 pass over pulleys 8 on the frame B, thence downward about pulleys 9 which are supported in brackets 10 fixed to opposite sides of the loading skip 11. The skip 11 is piv-

totally mounted on the frame B as shown at 12. After passing around the pulleys 9 the cables 7 lead upwardly from said pulleys to points of connection 13 adjacent to the 5 top of the frame B and approximately beneath the pulleys 8. The portion of each cable 7 between the associated pulleys 8 and 9 has affixed thereto a stop 14 held firmly in place on the cable by a clamp 15 but rendered adjustable so as to be fixed at different points in the length of the cable owing to the obvious adjustability of said clamp. The brackets 10 are of somewhat peculiar 10 form in that they are provided with rearwardly and upwardly curving extensions 16 forming abutments to coöperate with the stops 14.

The pulleys 9 are of peculiar form, each pulley being formed with a central circumferential cable groove 9' from which groove lead off series of oppositely extending snatch grooves 9'', thus constituting each of said pulleys 9 a snatch or clutch pulley.

The appliances forming parts of the operating connections intermediate the motor 5 and the loader or skip 11 are simple ones, the mechanical action of which is very largely evident with knowledge of their construction. It may be noted, however, that 20 when the drum 2 is operated by its cable 3 to thereby rotate the shaft 1, winding of the cables 7 upon the pulleys 6 takes place. The cables 7, furthermore, operate about the pulleys 9 affording a maximum of power 25 with slow movement during the initial raising of the skip 11 at which time, owing to the point of pivotal support of the skip, the load is largely dead weight, making necessary the application of sufficient power to 30 overcome the gravitational force of both the skip and the load. As the skip 11, however, reaches an approximately medial point in its movement, the stops 14 on the cables 7 abut with the abutments 16 and thereafter 35 the movement of the cables 7 is directly communicated to the skip as distinguished from the indirect communication incident to the pulley transmission devices 9 which were operative previous to the time of co-operation of the parts 14 and 16. The effective pull of the cable, therefore, is initially sustained by the points of connec- 40

tion 13 and subsequently by the stops 14 in an obvious manner, the portions of the cables 7 between the parts 13 and 14 becoming slack when the stops 14 sustain the load, as shown in dotted lines in Fig. 1.

In the event of breakage of the cable 7 at either side of the pulleys 9 the sudden slack created incident to the breakage causes a 60 side lash of the ends of the cables so as to make effective the snatch or clutch pulley 9 which will thus grip the cable and prevent accidental dropping of the load of the skip 11 and its contents, or the skip itself. 65 The pulleys 9 are therefore safety devices and are useful when the skip 11 is upraised and out of use, preventing dropping of the skip through cable breakage, as an incident to which accidental injuries to workmen are 70 caused from time to time in the operation of loading devices of this type.

It is notable that as the skip 11 is elevated from its lowermost receiving position the cone drums or pulleys 6 act with gradually increasing speed to effect the raising movement, due to the peculiar formation of said parts.

Having thus described my invention, what I claim as new is:

1. In combination, a support, a loading skip movably connected at one end therewith, raising means for said skip comprising a cable anchored at one end and passing around the pulley, means on the support for actuating the said cable, said pulley being formed with clutch grooves adapted to act automatically on breakage of the cable to prevent dropping of the skip.

2. In combination, a support, a skip pivoted at one end thereto, a pulley attached to said skip and formed with clutch grooves extending in opposite directions from its central circumferential portion, a hoisting cable anchored at one end to said support, 95 and thence passing downwardly over said pulley and upwardly to the support, winding means on the support about which said cable may pass, said arrangement of the cable providing spaced bights extending 100 from opposite sides of the pulley as and for the purpose described.

In testimony whereof I affix my signature.
ERICH H. LICHTENBERG.
